UNITED STATES PATENT OFFICE.

CEPHAS C. SHELURN, OF COLORADO, TEXAS.

PUMP.

SPECIFICATION forming part of Letters Patent No. 442,209, dated December 9, 1890.

Application filed August 12, 1890. Serial No. 361,781. (No model.)

To all whom it may concern:

Be it known that I, CEPHAS C. SHELURN, a citizen of the United States, residing at Colorado, in the county of Mitchell and State of 5 Texas, have invented certain new and useful Improvements in Pumps; and I do hereby declare the following to be a full, clear, and exact description of the invention, such as will enable others skilled in the art to which it applies 10 pertains to make and use the same.

My invention relates to pumps, more especially such as are used in connection with deep wells; and it consists in certain improvements in the construction of the same, as hereinafter set forth and described.

In the accompanying drawings, Figure 1 illustrates my improvements in side view, a working-barrel being shown in broken lines. Fig. 2 is a like section of the check-valve and 15 connections. Fig. 3 represents the check-valve and seat detached.

To the sucker-rod A is secured a valve-cage B, within which is loosely placed a valve C, which is provided with a hollow stem a, a 20 leather facing c, and a head b, the parts being secured by a bolt d, which extends up through the stem, and the head b, which is threaded and screwed to the upper end of said bolt. The valve-cage B is formed with the 25 interior guides e for the head b, said guides serving to keep the valve in position and prevent its tilting during its vertical movement.

A leather packing g is placed at the bottom of the cage B, surrounding the same, as shown.

D indicates a hollow cylindrical body, which is provided with a threaded annular flange i at the top, on which the valve C rests, and to which the cage B is screwed. The body D is tapered downward somewhat, as seen at f, 30 and terminates with an annular threaded flange m. Two cup-leathers n and o, one being within the other, inclose the tapered part of the body D and fit on the shoulder p, being secured by a hollow cylinder E, which is 35 screwed on the flange m. The two cup-leathers n and o form a double packing, and as the outer packing is worn away the inner one expands and takes its place.

At the lower end of the working-barrel is 40 placed a check-valve F in a valve-cage G, a seat being constructed for said valve in the following manner: A casing or shell H is secured to the lower end of the working-barrel, the said shell tapering downward and being

provided with an annular shoulder r, which 55 is formed on its inner surface near its lower edge. The seat J, which fits in the shell H, has a central opening surrounded by a flange s, so that an annular space is left between 60 said flange and the shell to receive the valve-cage G and the cup-leather u, fitting on the lower edge of said valve-cage. The seat J is also provided with bifurcations or downward extensions v, which set against the shell and rest on the shoulder r. The extensions v are 65 made thin enough to be somewhat elastic and yield to pressure when the seat J is placed in the shell; but the seat is connected with the check-valve and may be readily withdrawn with the latter when desired.

The check-valve F and cage G are similar in construction to the plunger-valve C and cage B before described. The cage G is connected with flange s of seat J, and is provided with packing u at the bottom. The top y of 70 cage G is provided with external and internal threads for the attachment of a rod, by means of which the valve F, with its cage and seat, 75 may be withdrawn from the working-barrel when desired.

I claim—

1. The combination, with the working-barrel, of a casing or shell secured to the lower end of said barrel, the said shell tapering downward and being provided with an annular shoulder r on its inner surface, a valve-seat provided with an annular flange s and downward elastic extensions constructed to close against said shell and rest on said shoulder r, and a valve-cage connected with said 85 seat and containing a valve, substantially as and for the purposes described.

2. The combination, with the working-barrel of a pump, of a shell H, attached to the lower part of said barrel and provided with 90 an inner shoulder r, the seat J, provided with flange s and elastic downward projections v, which set against the shell and rest on shoulder r, check-valve F, and cage G, the latter being connected with flange s and provided 95 with packing at its lower edge, substantially as herein set forth.

In testimony whereof I have affixed my signature in presence of two witnesses.

CEPHAS C. SHELURN.
